UNITED STATES PATENT OFFICE.

DAVID FINKELSTEIN, OF NEW YORK, N. Y.

RAILWAY-TRACK TRUSS.

1,233,861.

Specification of Letters Patent. Patented July 17, 1917.

Application filed May 3, 1917. Serial No. 166,119.

To all whom it may concern:

Be it known that I, DAVID FINKELSTEIN, a citizen of the United States, and resident of the city of New York, borough of the Bronx, county of Bronx, and State of New York, have invented a new and Improved Railway-Track Truss, of which the following is a full, clear, and exact description.

This invention relates to a railway track construction and has particular reference to means for supporting railway rails.

Among the objects of the invention is to provide supporting means for railway rails of such a nature as to reduce to a minimum (1) the deflection in the rails laterally as well as up or down, thereby producing a stiffer track; (2) the creeping of rails because of the decrease in the wave motion; (3) the cost of track construction, because of the fact that less depth of ballast is required to distribute the wheel loads to the subgrade; (4) the cost of track maintenance because resurfacing, and renewals of rails and ties will be less frequently required due to the stiffer track, better rail joints and better supported ties; and (5) the wear and tear on the rolling stock because of a smoother riding track.

Another object of the invention is to provide a railway rail supporting means of such a nature that the danger of derailment will either be prevented or lessened, such occurrences resulting under the old practice largely from the spreading of the rails and bad road bed which should not occur with my improvement in use.

Another object of the invention is to provide a better distribution of the wheel loads and the supporting power of the track structure which will tend to prevent damage to or failure of culverts. My construction furthermore being of a nature tending to prevent all deflection of the track rails in every direction will practically prevent the heaving of the track due to frost or the effect of great extremes of heat and cold.

A still further object of the invention is to provide a truss for railway tracks calculated to prevent all looseness of ties or damage to ties which is likely to result from crushing, spike killing, or cutting by the tie plate or rail.

A still further object of the invention is to alleviate, or reduce to a minimum, trouble due to faulty rail joints and hence the noise incident to loose joints will be eliminated.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation of a fragment of a railway track showing my improvement.

Fig. 2 is a plan view of the same on a smaller scale; and

Fig. 3 is a vertical transverse sectional detail on the line 3—3 of Fig 1; and

Fig 4 is a vertical sectional detail on the line 4—4 of Fig. 3.

Referring now more particularly to the drawings I show my improved railway track truss assembled in connection with any usual or conventional form of rails R and cross ties 10. I prefer to use wooden ties not only because of greater cheapness, but because of their superior qualities when connected or anchored as they are by my improved truss. By my improvement I am able to construct a road bed having suitable strength or wear resisting qualities but still employing ties of ordinary or even inferior quality, an item of extreme importance economically in view of the present cost of ties. I wish to observe in this connection also that with my improved truss the ties though of common quality may be spaced farther apart than under other systems. In carrying out my improvement in a practical embodiment I provide a pair of upper and lower longitudinal members which for convenience I shall refer to hereinafter as straps 11 and 12. These straps may be of any suitable relative lengths, but are preferably coextensive in length longitudinally of the track, and may also be regarded as continuous as distinguished from short braces that pertain only to individual ties. The strap 11 lies across the top of each tie and directly beneath the rail. That portion of the strap 11 lying between the rail and the tie may constitute a tie plate 13 of any suitable length or width, but serving to take the place of the usual, more or less troublesome, separate tie plate. These tie plates 13 are preferably formed integral with the strap 11, but as to this detail of construction as

well as other details I do not propose to be unnecessarily restricted in practice. That portion of the strap 11 between each two adjacent ties is deflected downwardly as indicated at 11' to about the horizontal plane of the centers of the ties where there is formed a flat section 14 having a vertical hole therethrough. The inclined portions of the strap between the flat section 14 and 10 the plates 13 are preferably straight and hence possess maximum stiffness and strength.

The strap 12 in side view approximates the form of the strap 11 but lies beneath all 15 of the ties directly below the rail and upper strap 11 and is deflected upwardly at 12' between each two adjacent ties. The top of the deflected portion is indicated at 15 and lying flat against the flat portion 14, it being 20 provided with a hole therethrough registering with the hole in the flat part 14 through which a strong fastening device of any suitable nature but indicated as a bolt 16, with threaded nut 17, passes, constituting a suitable locking means from one strap to the 25 other in the space between adjacent ties.

The straps 11 and 12 are made of any suitable metal of sufficiently good quality and weight for the purpose intended and may be 30 secured to the ties in any suitable manner. Preferably, however, the lower strap 12 requires no special or direct attachment means to the ties.

The tie plates 13 in the form of the invention disclosed herein constitute means for securing the top strap and ties to one another. Each tie plate is shown provided with a pair of holes 18 at its inner corners and with a central outwardly projecting lug 19 having 40 a central hole 20. The corners of the plate adjacent to the lug 19 are bent upwardly and inwardly toward the rail forming hooks 21 which engage firmly over the outer edge of the rail base flange 22. Any 45 suitable fastening spikes, preferably screw spikes 23, may be employed to pass through the holes 18 and 20 to lock the tie plates to the ties.

The outer edges of the base flanges 22 of 50 the rails being locked beneath the hooks 21 the inner edges of the same flanges may be locked to the inner ends of the tie plates by any suitable means, but for this purpose as set forth herein I propose to employ a series 55 of keepers 24 each having a flat portion with a hole registering with one of the holes 18 and through which a special fastener 23' passes and also having a lip gripping firmly down upon the top of the base flange. These 60 keepers serve by abutting substantially against the extreme edge of the base flange to prevent lateral movement or looseness of the rails as well as to prevent tilting of the rails or up or down movement thereof. It 65 will thus be seen that all of the ties are

effectually interlocked with one another through the longitudinal straps, that the straps are reliably secured to each other and to the ties, and that the rails are reliably anchored to the tie plates constituting a part 70 of or otherwise secured to the truss structure. It is also to be noted that the diagonal portions of the straps or the parts deflected toward each other at or about the centers of the ties, being very strongly and firmly secured together, afford a very strong and rigid construction, reliably preventing all track deflection as well as tendency for individual ties to be damaged or displaced. By the provision of the special fastener 23' 80 the rails and tie plates may be so secured or clamped together that any tie may be removed or replaced without disturbing the connection between the rails and the tie plates. 85

I claim:

1. In a railway track truss, the combination with a series of ties, of continuous longitudinal strap members embracing all of said ties, said strap members lying one above 90 the other, and means securing the straps to each other between the ties.

2. In a railway track truss, the combination with a series of ties, of a pair of longitudinal continuous strap members embracing 95 the ties and deflected between the ties toward the horizontal plane of the centers of the ties, and means to lock the deflected portions of the straps together.

3. In a railway track truss, the combination with a series of spaced ties, of a continuous strap lying upon the upper faces of all of the ties, means to secure the strap to the ties, a continuous strap extending beneath all of the ties, and means connecting 105 those portions of the straps between adjacent ties together.

4. In a railway track truss, the combination with a series of spaced ties, of a continuous strap member lying on top of all of the ties, a second strap extending beneath all of the ties, said second strap being deflected upwardly between the ties to meet the first mentioned strap, and fastening means interlocking the meeting portions of the 110 straps strongly and rigidly together.

5. In a railway track truss, the combination with a series of spaced ties, of a continuous truss strap lying over all of the ties, means to fasten a rail directly upon said 120 strap and to the ties beneath, truss means extending along beneath the ties and directly below the strap aforesaid, and means to anchor said last mentioned truss means to those portions of the strap between the ties. 125

6. In a railway track truss, the combination with a series of ties and a rail extending longitudinally across the same, of a pair of continuous straps located one directly above and the other directly below the ties 130

and one strap being directly below the other, anchoring means for the upper strap constituting tie plates upon which the rail is supported, and means to anchor directly together the two portions of the straps between adjacent ties.

7. In a railway track truss, the combination with a series of cross ties and a rail extending across the same, of a continuous truss structure comprising a pair of coöperating straps embracing all of the ties beneath the rail, and means to anchor the straps to the ties and to each other.

8. In a railway track truss, the combination with a series of spaced ties and a rail extending longitudinally across the same, of a pair of continuous straps extending from each tie to the next and spanning the spaces between them, said spanning portions of the straps being deflected to meet each other midway between the ties, and means to anchor said deflected portions of the straps together.

9. In a railway track truss, the combination with a series of ties and a rail above the same, of a pair of continuous coextensive strap members embracing all of the ties be-

neath the rail, portions of both straps between adjacent ties being inclined, and means to anchor the straps and the rail to the ties.

10. In a railway track truss, the combination with a series of ties, of a pair of strap members embracing all of said ties, one strap lying above all of the ties of the series and the other strap lying below the same, and locking means from one strap to the other in the space between the ties.

11. In a railway track truss, the combination with a series of ties, of a continuous truss strap lying over all the ties of the series, means to fasten said strap to the ties, a rail supported upon the strap, means to fasten the rail in place upon the strap, truss means extending beneath the ties below the strap, and fastening means for the last mentioned truss means.

12. The combination with a series of cross ties and a rail extending across the same, of a continuous truss structure comprising a pair of coextensive coöperating straps embracing said ties beneath the rail, and means to secure said truss structure to the ties.

DAVID FINKELSTEIN.
